UNITED STATES PATENT OFFICE.

WARREN J. MOREHOUSE, OF ASHTABULA, OHIO.

RAILWAY-RAIL JOINT.

1,078,743.

Specification of Letters Patent. Patented Nov. 18, 1913.

Application filed July 2, 1913. Serial No. 777,078.

To all whom it may concern:

Be it known that I, WARREN J. MOREHOUSE, a citizen of the United States, residing at Ashtabula, in the county of Ashtabula and State of Ohio, have invented certain new and useful Improvements in Railway-Rail Joints, of which the following is a specification, reference being had to the accompanying drawings.

10 This invention relates to railway rail joints, and it more particularly relates to an improved form of railway rail and fish plate.

15 An object of the invention is to provide an improved form of railway rail in which the use of bolts may be entirely dispensed with.

20 Another object of the invention is to provide a rail joint of this character by means of which the rail ends are securely fastened together and held rigidly in alinement.

25 Another object of the invention is to provide rails and rail joints of this character which are comparatively inexpensive, strong, durable, and thoroughly efficient and effective.

Other objects and advantages may be recited hereinafter and in the claim.

In the accompanying drawings, which 30 supplement this specification, Figure 1 is a side elevation view of two adjacent rail ends constructed in accordance with my invention; and Fig. 2 is an end view of one of the rails having my improved fish plates 35 fitted thereto, the latter being illustrated in section.

In these drawings, in which similar reference characters correspond with similar parts throughout the several views, the rail 40 heads 5 are somewhat deeper or thicker than those ordinarily constructed, for the provision of depending flanges 6 and longitudinal grooves 7, said grooves being located between the web 8 and the respective flanges 6.

45 The base flanges 9 are each provided with an upstanding flange 10 which extends longitudinally of the rail in the vertical plane of the respective flanges 6, so as to provide grooves 11 which extend longitudinally of 50 the rail between the web 8 and the respective flanges 10, said grooves 11 being directly under and in the vertical plane of the respective grooves 7.

The upper and lower portions of the web 55 8 diverge outwardly on an even curve, so as

to form concaved bearings or seats 12 in which one edge of the fish plates 13 is fitted; each fish plate 13 having its respective upper and lower edge portions convexed as at 14, and adapted to be seated in the concaved portions 12, at the adjacent ends of the rails. The convexed portions 14 and the outer edge portions 15 are provided with corrugations or teeth 16, which accomplish the several functions hereinafter recited. 60

It is well known that in railway rails which are manufactured by the usual process of "rolling," the surfaces thereof are left in a comparatively rough and uneven state. That is, such rails are not formed with polished surfaces or with such perfectly even 70

surfaces as if the rails were planed or polished. Therefore, it is desirable to form the fish plates with said corrugations, or with alternating teeth and notches, so that when 75 said fish plates are driven or forced into the notches 7 and 11, said teeth remove the particles of scale and other unevennesses from the surfaces 12, while the notches between the teeth receive such particles that have 80 been removed from said surfaces 12. In other words, the fish plates cut their way into the seats between the depending and upstanding flanges. Likewise, such unevennesses that cannot be removed by the teeth 85

16 cut or force their way through said teeth; and so, it will be seen that the teeth or corrugations 16 compensate for shrinkage and other causes of variation in the dimensions, which would otherwise either prevent entrance of the fish plates or allow them to 90 enter too easily and fit too loosely in their respective seats.

In applying the fish plates to the rails, the latter are first laid in place, the fish 95 plate is then driven into the grooves 7 and 11 thereof by means of a sledge or other suitable tool. The rail ends are now held securely together by means of the fish plates, while the fish plates, in turn, are held in 100 their seats by the flanges 6 and 10 of the rails. It is obvious that, during expansion and contraction of the rails, the fish plates have slight relative movement within their seats, upon the surfaces which have thereby 105 been rendered relatively smooth, while the relatively rough portions of the surfaces 12, over which the teeth 16 have not traveled, prevent the fish plates from moving away from the rail ends. 110

The fish plates 13 are preferably concavo-convexed. That is, they are convexed or bowed outwardly, as at 17, and these fish plates are made of somewhat springy material, (preferably steel), so that when the teeth 16 and the adjacent surfaces 12 become worn from constant expansion and contraction of the rails, the tension is maintained by the spring action of the bowed portion 17, which constantly presses the teeth into frictional engagement with the surfaces 12.

It will be seen that I have provided a railway rail and rail joint of this character which is fully capable of attaining the foregoing objects in a thoroughly practical and effective manner.

While the accompanying drawings illustrate what I believe to be the preferred embodiment of my invention, it is to be understood that the invention is not limited thereto, but that various changes may be made in the construction, arrangement and proportions of the parts without departing from

the scope of the invention, as defined in the 25 appended claim.

I claim—

The combination in a railway rail joint, of two adjacent rail ends each having an upper flange depending from its head and a lower flange extending up from the base flange of the rail, said upper and lower flanges being spaced apart from the respective webs of the rail ends and being in parallel relation with said web, and a fish plate 30 of springy material and being bowed outwardly and having its upper and lower edges seated between the rail web and the respective upper and lower flanges and held in frictional engagement with said rail ends 35 by the spring action of the bowed portion.

In testimony whereof I hereunto affix my signature in the presence of two witnesses.

WARREN J. MOREHOUSE.
